UNITED STATES PATENT OFFICE

HAROLD V. TAYLOR, OF MONTREAL, QUEBEC, CANADA, ASSIGNOR TO THE ROBERT MITCHELL COMPANY LIMITED, OF MONTREAL, QUEBEC, CANADA

SASH GUIDE FOR WINDOW FRAMES

Application filed May 26, 1930. Serial No. 455,851.

This invention relates to windows and comprises an improved sash assembly.

An object of the invention is to provide a sash assembly including means for maintaining the meeting rails of the upper and lower sashes in such tight engagement as to eliminate the need of weatherstripping at this point.

Another object is to provide a metal sash assembly in which the lower sash is mounted to slide in vertical channels comprising upper and lower sections, the lower sections being displaceable with reference to the upper sections to facilitate application and removal of the sash.

A further object is to provide a sash assembly in which the sections of the lower sash guide are conveniently constructed of sheet metal and attached to a common base strip to provide a self-contained unit of inexpensive construction adapted to be readily applied to a window frame or removed therefrom.

Further objects and advantages of the invention, as well as the characteristic features of the embodiments herein disclosed will be more readily understood from the following detailed description taken in connection with the accompanying drawings, in which

Figure 1 is a side elevation of a window equipped with a sash assembly constructed in accordance with the present invention.

Figure 2 is a perspective view showing the manner in which the lower sections of the guides for the sliding sash may be displaced with reference to the upper guide sections to facilitate application and removal of the sash. In this view, portions of the window frame and the upper sash are broken away to show part of the means for holding the upper sash in position.

Figure 3 is a transverse sectional view taken substantially along the line 3—3 of Figure 1.

Figure 4 is a vertical sectional view taken along the line 4—4 of Figure 1. In this view the upper and lower sashes have been omitted in order that the means for mounting said sashes may be clearly seen.

Figure 5 is a view in perspective showing

the parts of the lower sash guide in disassembled relation.

Figure 6 is a view in elevation showing the lower sash guide as the latter appears when the upper and lower guide sections are in aligned position. 55

Figure 7 is a view similar to Figure 6 but showing the lower section of the guide displaced with reference to the upper sections to facilitate application or removal of the sash. 60

Figure 8 is a sectional view taken along the line 8—8 of Figure 7.

Figure 9 is a fragmentary sectional view showing the manner in which the lower sash may be provided with spring means adapted to co-operate with the sash guide to prevent rattling of the sash in the guide and also to hold the upper rail of the lower sash in tight engagement with the meeting rail of the lower sash. 65

Figure 10 is a fragmentary perspective view showing certain modifications with respect to the guide sections for the lower sash.

Figure 11 is an edge view of the construction shown in Figure 10. In this view the guide sections are shown in aligned position. 75

The upper part of the window frame, indicated at 11, is closed by a stationary sash 12. A flange 13 at the upper edge of this sash is fastened by screws 14 to a transverse strip 15 carried by the window frame. The side edges of sash 12 are held in place by metal strips 16 provided with sash retaining flanges 17. The metal strips 16 are spaced from the window jambs 18 by flanges 19 and spacing sleeves 20. Anchoring screws 20a are passed through the strips 16 and through the sleeves 20 into the jambs 18. 80

The side edges of the lower sash 21 are arranged to slide in suitable channel guides attached to the jambs 18 and extending the full height of the window frame. Each channel guide comprises an upper stationary section 22 and a lower pivotally mounted section 22a. Both sections are formed from a single strip of metal bent to provide spaced side flanges 23 and 23a connected by an intervening web 24. The web 24 of section 22 is fastened by screws 25 to the web 26 of a channel shaped base strip, including side flanges 100

27 and 27a. This base strip is arranged with its web 26 spaced from the window jamb 18 by the flanges 27 and 27a and is also provided with a further flange 28 which is preferably formed as an integral continuation of the flange 27 and disposed to project beyond the web in the opposite direction. At its lower end, the web 24 of the channel guide section 22a is secured by a pivot 29 to the web 26 of the base strip, whereby section 22a is mounted to swing into and out of alignment with the upper stationary section 22. When sections 22 and 22a are aligned, as shown by full lines in Figure 3, the flange 28 of the base strip serves as a weatherproofing element to prevent the entrance of air or moisture between the web 26 of the base strip and the engaging webs 24 of the guide sections 22 and 22a. Guide sections 22 and 22a may likewise be provided with weatherproofing flanges 30 formed as reverse continuations of the sash engaging flange 23a and arranged to overlap the flange 27a of the base strip. The web 26 of each base strip and the engaging web 24 of the pivotally mounted guide section 22a are provided with normally registering openings 32 for receiving the bolt or detent (not shown) carried by one of the sash locks indicated at 33 in Figure 1. When the complementary sections 22 and 22a of each guide are aligned as shown in Figure 3, they form a continuous guide channel for the sash 21 extending from the bottom to the top of window frame 11. When sash 21 is positioned between the complementary sections 22a of the opposed guides and it is desired to remove the sash this is easily accomplished by swinging said sections 22a about their pivots 29 to the position shown in Figure 2. In this position of guide sections 22a, the sash 21 may be readily removed by drawing the sash upwardly and outwardly along the channels provided between the sash engaging flanges 23 and 23a.

The complementary sections 22 and 22a of each guide are formed with inclined meeting edges 34 and 35 adapted for abutting engagement to limit swinging movement of section 22a in the direction of section 22. Swinging movement of section 22a in the opposite direction is limited by a member 36 carried by section 22a and operating in slots 37 and 38 formed, respectively, in the side flanges 27 and 27a of the base strip. Member 36 carries a stop lug 39 adapted to engage a portion of the flange 27a surrounding the opening 28. The slot 37 is made larger than the slot 38 to permit free passage of the member 36 and stop lug 39 when the section 22a is swung to an aligned position with reference to the section 22.

As shown to advantage in Figure 8, a space 41 is reserved between the member 36 and the web 24 to receive the web 26 of the base strip

when the guide sections 22 and 22a are aligned.

The guide sections 22 and 22a may be secured in aligned position by means of a screw 42 carried by the web 26 of the base strip. The head of this screw is adapted to engage with registering countersunk notches 42a formed in the meeting edges 34 and 35 of the guide sections. When the screw 42 is backed off to remove the head thereof from engagement with the notches 42a, the section 22a is free to swing outwardly with reference to section 22. The arrangement is such that the shank of screw 42 does not interfere with the movement of section 22a when the head of the screw is disengaged from the notches.

As shown by way of suggestion in Figure 9, each side rail of the sliding sash 21 may be provided with one or more springs 43 adapted to engage the flanges 23a of the guide sections 22 and 22a. These springs prevent rattling of the sash in the guides and also serve to press the upper rail of the sash 21 tightly against the lower or meeting rail of the sash 12. In order to permit the meeting rails of the sashes 12 and 21 to be thus maintained in tight engagement with one another, the sash 12 is formed as shown to advantage in Figure 3. In this figure, it will be noted that the frame of sash 12 is made wider than the metal strip 16 engaging the side stiles of said frame. The marginal portions of the side stiles which project inwardly beyond the strips 16 are recessed as indicated at 47 to receive the flanges 28 of the base strip and the flanges 23 of the channel guide sections 22 and 22a. This recessing of the sash 12 and the disposal of the flanges 28 and 23 in said recesses permits the bottom rail of sash 12 to be disposed with its inner surface flush with the inner surface of the flange 23 so as to be engaged by the top rail of the lower sash 21. The engaging rails of the two sashes are maintained in such tight engagement by the springs 43 that weatherproofing contact is obtained without the use of weather stripping.

In the modifications disclosed in Figures 10 and 11 a fastening bolt 48 is substituted for the fastening screw 42 previously described. This bolt 48 is mounted to slide in a bearing 49 provided in the channel formed between the flanges 27 and 27a of the base strip. One end of the bolt 48 is bent to provide a handle portion 50 projecting outwardly through a slot 51. The other end of the bolt is adapted to co-operate with a notch 52 formed in the stop member 36 carried by section 22a. When it is found desirable to provide means for holding the guide sections 22a in the outwardly swung position shown in Figure 2, this may be conveniently accomplished by the provision of spring fingers 54 carried by the base strip and bearing against the stop member 36, as shown to advantage in Figure 10.

In Figures 10 and 11 the weatherproofing flanges 28 and 30 have not been shown as these flanges while important from a weatherproofing standpoint, may be omitted if so desired.

5 From the foregoing it will be manifest that my invention provides an all-metal sash mounting composed mainly of parts capable of being produced by simple shaping operations without the use of special tools or dies. The sectional structure of the guide for the lower sash enables said sash to be easily applied or removed, while the attachment of the sections of each guide to a common base strip provides a unit assembly which greatly 10 facilitates application and removal of the guide with reference to any type of window frame.

Having thus fully described what I now conceive to be the preferred embodiment of my invention, it will be understood that various modifications may be resorted to within the scope and spirit of the appended claims.

Having thus described my invention, what 25 I claim is:—

1. A sash guide assembly comprising a base strip adapted to be detachably secured to the ordinary jamb of a window frame and complementary sash guiding and retaining sections secured to said strip to form a unit therewith, one of said sections being movable into and out of alignment with the complementary section.

2. A metal sash guide assembly comprising a base strip, upper and lower complementary sash guiding and retaining sections secured to said strip with one of said sections mounted for lateral displacement with reference to the complementary section, said strip and sections being assembled together to form a self-contained unit capable of being applied to a window frame by attaching said base strip to one of the jambs of said frame.

45 3. A sash guide assembly comprising a base strip, complementary sash guiding and retaining sections secured to one face of said strip, one of said sections being movable into and out of alignment with the complementary section, and weatherproofing elements carried by said sections and adapted in the aligned position of the sections to bridge the space between said sections and the aforementioned face of the base strip.

55 4. A sash guide assembly comprising a base strip, complementary sash guiding and retaining sections secured to said strip, one of said sections being movable into and out of alignment with the other section and weatherproofing elements carried by said strip and by said sections and arranged to seal the space between the strip and sections in the aligned position of the latter.

65 5. A sash guide assembly comprising a base strip, complementary sash guiding and

retaining sections carried by said strip, one of said sections being stationary on the strip and the other section being connected to the strip for movement into and out of alignment with the stationary section, each of said sections comprising side flanges extending in a direction away from the base strip and connected by an intervening web, the latter being secured to said base strip. 70

6. A sash guide as recited in claim 5 including a weatherproofing flange carried by each of said sections and extending in a direction opposite to the first mentioned flanges for engagement with one side of the base strip. 75

7. A sash guide as recited in claim 5 including a weatherproofing flange carried by the base strip for engagement with said sash guiding and retaining sections. 80

8. A sash guide comprising a base strip, complementary sash guiding and retaining sections carried by said strip, one of said sections being stationary on the strip and the other section being connected to the strip for movement into and out of alignment with the stationary section, each of said sections comprising side flanges extending away from the base strip and connected by an intervening web, the latter being secured to the base strip, weatherproofing flanges also carried by each of said sections and adapted to engage one side of the base strip and a further weatherproofing flange carried by the opposite side of the base strip and adapted to engage said sections. 85

9. A sash guide comprising a base strip of channel section, including side flanges connected by an intervening web, said strip being adapted to be attached to a window jamb with the web spaced from said jamb by means of said flanges, upper and lower sash guiding sections of channel form carried by said base strip, each of said sections including a web bearing against the web of the base strip and provided with said flanges projecting in a direction away from the base strip, one of said guide sections being stationary on the base strip and the complementary guide section being pivotally secured to said base strip for movement into and out of alignment with the stationary section. 105

In witness whereof, I have hereunto set my hand.

HAROLD V. TAYLOR.
